Q.S. 2364

John H. Bellamy, Charlestown, Mass.

Assignor to

David A. Cutcomb, for $\frac{1}{2}$ said Invention

Letters Patent No. 2364, Dated July 04, 1866,

Design for a Bracket.

The Schedule referred to in these Letters Patent and making part of the same,

To whom it may concern:

Be it known that I, John H. Bellamy of Charlestown
in the County of Middlesex and State of Massachusetts, have invented
or produced a new and Original Design for a Bracket, and I do
hereby declare that the following is a full and exact description
of the same:

The nature of my invention consists of a new and original
Design for a bracket as follows to wit: The back A, above the shelf B,
consists of a scroll C, on either side joined at the top by three links 1, upon
which rests an open hand 2, with a heart 3, in the palm, passing through
the middle link is an axe 4, and beneath which are three arrows 5, and
a bee hive 6, on the right and left of said bee hive, there being scales 7,
and a word 8. Beneath the shelf B are three pillars 9, whose bases
rest upon scrollwork 10, the shelf B being supported by an ornamental
scroll E, the whole being substantially set forth in the drawing.

I claim as my invention and desire to secure by Letters Patent
the Design for a Bracket substantially as shown and described.

Witness,

Wad D. Dunton,

Joseph H. Bellamy.
